CLAIM

The ornamental design for a dispensing device, as shown and described.

DESCRIPTION

FIG. 1 is a front elevational view of our new design, the rear elevational view being the same;

FIG. 2 is a right side elevational view of our new design, the left side elevational view being the same;

FIG. 3 is a bottom plan view of our new design; and,

FIG. 4 is a top plan view of our new design.

The broken lines showing crescent-shaped semi-circular dispensing orifices on FIGS. 1, 2 and 4; and the circle on FIG. 3 are for illustrative purposes only and do not form part of the claimed design.
